Japan, a corporation of Japan

Application June 4, 1935, Serial No. 24,839
In Japan August 13, 1934

4 Claims. (Cl. 250—20)

This invention relates to radio receiving systems and more particularly to detecting systems therefor, in which thermionic tubes are operated with A. C. anode current of approximately saturation value.

An object of this invention is to obtain very sensitive detection of received waves with a tube which is so operated that its A. C. anode current varies according to drooping characteristics.

10 Another object of this invention is to provide an improved autodyne system for obtaining detection on the heterodyne principle with a single tube operating as a detector and as a local oscillator, in which a more sensitive detection is obtained than in the ordinary autodyne system.

15 A further object of this invention is to provide a single-tube zero-beat detecting system having a high sensitivity.

20 A still further object of this invention is to provide a power amplifying and detecting system having a high sensitivity.

25 There are other objects and particularities of this invention, which together with the nature and construction of this invention, will appear in the following description with reference to the accompanying drawing, wherein

Fig. 1 shows diagrammatically an ordinary autodyne radio receiving system.

Fig. 2 is a diagram showing the dynamic characteristic curves of the system shown in Fig. 1.

30 Fig. 3 shows diagrammatically one embodiment of this invention.

Fig. 4 is a diagram showing the dynamic characteristic curves of the system shown in Fig. 3.

35 Fig. 5 shows a modification of the system shown in Fig. 3.

Fig. 6 shows diagrammatically another embodiment of this invention which enables power amplifying detection with a high sensitivity.

40 This invention will best be understood with reference to the ordinary autodyne system shown in Fig. 1. The system comprises a resonance circuit 1 which is tuned exactly to local oscillation frequency f_2 and approximately to incoming oscillation frequency f_1 from an antenna 2 and connected to the grid and cathode of an ordinary three-electrode thermionic tube 3. The tube 3 has its anode circuit in feed-back coupling with the resonance circuit 1 through a coupling coil

45 4, and the local oscillation is superposed on the incoming oscillation in the circuit 1. The frequencies f_1 and f_2 are so selected that there is created a beat having a frequency (f_1-f_2) or (f_2-f_1) . This beat is detected or rectified by the 50 tube 3 and transmitted to the receiver 5 through

an intermediate-frequency amplifier and a second detector as usual. The coupling coils 6 between the anode circuit of the tube 3 and the succeeding stage i. e. the intermediate-frequency amplifier is provided with a by-pass condenser 7 for the local oscillation f_2 . This condenser provides a high impedance to the beat frequency and the latter passes through the primary coil 6.

5 It is well known that such a system of heterodyne principle as shown in Fig. 1 has very low 10 sensitivity because of the fact that it operates near the saturation point of the dynamic characteristic curve, if the oscillation stiffness is made so high that the local oscillation is maintained 15 steady.

Referring to Fig. 2, curve I_p shows the anode current, while curve I_g shows the grid current, with respect to the grid potential E_g of the tube 3. As is well-known, the drooping characteristic shown of the anode current curve I_p is due to the high potential drop across the coil 4 which is coupled to the resonance circuit 1 and consequently provides a very high impedance to the local frequency f_2 . In order to maintain the local oscillation f_2 generated by the tube 3 steady, the oscillation stiffness must be so high that the tube 20 operates near the saturation point A of the anode current curve I_p . Under the circumstances, the beat (f_1-f_2) or (f_2-f_1) exciting the grid of the tube 3 cannot sensibly be detected. 25 This is true even with multi-grid tubes when detected output is to be obtained from the anode circuit.

30 According to this invention, a thermionic tube having an additional grid is used in place of the tube 3, and the output circuit is connected to this additional grid. Referring now to Fig. 3, a resonance circuit 11 is coupled with the antenna 12 and is tuned exactly to the local frequency f_2 and approximately to the incoming frequency f_1 , 35 the local oscillation f_2 being fed by a thermionic tube 13 to the circuit 11 through a coil 14 inductively coupled therewith. The tube 13 comprises a cathode 21, an anode 22, a control grid 23 and a second grid 24 disposed between the anode and the control grid. The second grid 40 may, for example, be the screen grid of RCA—24—A tube or RCA—57 tube, or the acceleration grid of RCA—47 tube.

45 The local oscillation feed-back circuit is formed between the anode 22 and the cathode 21 through the coil 14 and a stopping condenser 25 for preventing direct current flowing there-through, and the anode 22 is energized to a positive potential by a battery 26 through a choke 50

coil 27 for preventing the oscillation current flowing therethrough. The screen grid 24 is connected to one end of a coupling transformer 16, the other end thereof being connected to the 5 cathode 21 through the battery 26. A condenser 17 provides a low impedance by-pass around the transformer 16 for the frequency f_2 . The direct current resistances offered by coils 14, 27, 16 and 56 are negligible. The anode should be maintained at a high direct voltage not materially lower than that of the second grid. It is not always intended to maintain the second grid at a higher direct current than the anode, but the former may be substantially equal to the latter. 10

15 With the above arrangement, the anode current I_p still has a drooping characteristic as shown in Fig. 4 due to the high impedance of the coil 14 coupled to the resonance circuit 11, but the screen grid current I_{sg} has a sharp rising characteristic, especially from the approximate point B corresponding to the saturation point A of the anode current curve. According to this invention, this screen grid current is utilized for detecting purpose near the point B, and a very sensitive detection is secured. The output of the beat or intermediate frequency is transmitted to succeeding amplifier 28 and detected by second detector 29 which in turn supply low frequency waves to amplifier 30, and the signal is received 30 by a receiver 15.

Although signal E_g without modulation is illustrated in Figs. 2 and 4, it is obvious that the above description is true also when the signal has voice modulation.

35 In the ordinary autodyne system, it must also be noted that the control grid current I_g becomes very high as shown in Fig. 2 due to the fact that when the grid potential E_g is near the positive maximum, the anode potential becomes less positive or more negative. This increase in grid current is undesirable because it increases the damping coefficient of the tuned circuit. Contrary to this, according to this invention, the control grid current I_g is kept sufficiently low to 40 maintain the damping effect very low.

45 With the arrangement shown in Fig. 3, when the local frequency is synchronized with the incoming frequency, that is to say $f_1=f_2$, it is obvious that a zero-beat detection is effected with a 50 very high sensitivity.

A portion of the arrangement shown in Fig. 3 may be modified as shown in Fig. 5. In this modification, the local oscillation circuit and incoming frequency circuit are separated from each 55 other, the anode load circuit for the local oscillation being formed between the anode 22 and the cathode 21 by a condenser 41 and an inductance coil 42 which is inductively coupled to a coil 43 in the grid return circuit. The operation of 60 this modified arrangement is quite similar to that shown in Fig. 3.

65 Generally stated, the operation of an oscillator tube is equivalent to that of an amplifier tube with a high grid excitation voltage, and the feature of this invention embodied in the arrangement shown in Fig. 3, is also applicable to power amplifying detectors in which the grid excitation voltage is made very high.

70 Now referring to Fig. 6, an antenna 51 is supplied with energy from a local oscillation generator 52. This energy is superposed on the incoming energy, and a very high potential is applied to the control grid 23' of the tube 13' which is similar to the tube 13 shown in Figs. 3 and 5. 75 The output circuit for the amplified oscillation

is formed between the anode 22' and the cathode 21' by a condenser 53 and an inductance coil 54 through a D. C. stopping condenser 55, while the D. C. circuit is formed between the same electrodes through a choke coil 56 and a high potential battery 57. According to this invention, the screen grid 24' is used for detected-waves output circuit and is connected to the positive terminal of the battery 57 through a coupling transformer 16' provided with a by-pass condenser 17' for high frequency waves, and the detected waves in the screen grid circuit is transmitted to the succeeding stage, not shown, by the transformer 16'.

10 As will be obvious from an inspection of the several forms of this invention as exemplified in the drawing, a feature common to all of such forms is resident in the fact that a thermionic tube having a cathode, an anode, a control grid and a second grid disposed between the anode and the control grid is used, and the second grid is utilized to obtain the output. By such arrangement, a very sensitive detection is effected in a radio receiving system, in which a thermionic tube is operated near the saturation point of its anode current curve and the detecting sensitivity 15 is, otherwise, consequently very low.

I claim as my invention:—

1. In a detecting circuit for radio receiving system, the combination with a thermionic tube having an anode, a cathode, a control grid and a second grid disposed between said anode and said control grid and to be operated with A. C. anode current of approximately saturation value, of means for generating high frequency oscillation including said anode and said control grid, and means for obtaining output including said second grid, means for applying a unidirectional potential to the electrodes and for maintaining said anode to a high direct voltage not materially lower than that of said second grid. 30

2. A detecting circuit for radio receiving system, comprising means for generating a local oscillation, a resonance circuit substantially tuned to incoming frequency and to the frequency of said local oscillation, a thermionic tube having an anode, a cathode, a control grid and a second grid disposed between said anode and said control grid, said control grid being excited from said resonance circuit, an anode load circuit for said local oscillation connected to said anode, an output circuit connected to said second grid, means to apply a unidirectional potential to the electrodes and to maintain said second grid to a high direct voltage with respect to said cathode, and said anode to a high direct voltage not materially lower than that of said second grid. 40

3. A radio detecting system comprising a resonance circuit substantially tuned to incoming frequency, a thermionic tube having an anode, a cathode, a control grid and a second grid disposed between said anode and said control grid, said control grid being excited from said resonance circuit, a feed back circuit connected to said anode for producing a local oscillation, means for coupling together said resonance circuit and said feed back circuit to produce a beat frequency, an output circuit for said beat frequency including said second grid, and a high direct voltage source with its positive terminal connected to said second grid and to said anode with its negative terminal connected to said cathode, said output circuit further including a coupling transformer with a high frequency by-pass condenser. 60

4. A radio receiving system, comprising an antenna, an input circuit receiving energy from 70

said antenna, a local oscillation generator for supplying energy to said input circuit, a power amplifier tube having an anode, a cathode, a grid and a second grid, said first-mentioned grid being excited by high alternating current potential from said input circuit, means for applying a high positive direct voltage to said second grid, means for applying a unidirectional potential to the elec-

trodes and for maintaining said anode to a high positive direct voltage not materially lower than that of said second grid, an anode load circuit for the local oscillation formed between said anode and said cathode, and an output circuit formed between said second grid and said cathode.
